UNITED STATES PATENT OFFICE.

CLEMENS A. HAASS, OF BOSTON, MASSACHUSETTS, ASSIGNOR TO TATE MANUFACTURING COMPANY, OF BOSTON, MASSACHUSETTS, A CORPORATION OF MASSACHUSETTS.

DAUBER FOR LIQUID BLACKING AND THE LIKE.

Application filed April 28, 1922. Serial No. 557,130.

To all whom it may concern:

Be it known that I, CLEMENS A. HAASS, a citizen of Germany, residing at Boston, in the county of Suffolk and State of Massachusetts, have invented certain new and useful Improvements in Daubers for Liquid Blacking and the like, of which the following is a specification.

My invention is an improved swab or dauber, particularly intended for use in connection with liquid blacking, but adapted also for other uses, in spreading and applying other liquid substances, such as stains, polishes, varnish and the like.

15 Swabs have hitherto been made, for such uses, in which a bunch of fibers or a piece of fabric has been attached to one end of a wire or stick, no regard being paid to the shape of the swab nor its construction, to enable it to take up, without dripping, the largest amount of liquid material and to apply that material in the best possible manner and so as to permit of a strong construction at minimum expense.

25 The object of my present invention is to provide a swab presenting large and smooth applying surfaces, secured firmly, by simple means, at the end of a holding rod, and provided also with narrow channels in the body of the material for receiving and retaining by capillarity a body of liquid and feeding it out in the use of the swab. In the preferred form this swab and holding rod is combined with a cork for the bottle 30 in which the liquid is contained.

In the drawings:

Figure 1 is a perspective view of a sheet of felt or the like, partially grooved, as the first step in the process of forming the 40 swab;

Figure 2 is an end view of two strips, cut from the grooved sheet of Figure 1;

Figure 3 is a perspective view of a block or length cut from the strip of Figure 2, with the bottoms of the two grooves pulled together by a loop of wire, and is a section on line 3—3 of Figure 5;

Figure 4 is a side view of the swab-block and loop before the pressure is applied;

50 Figure 5 is a side view of the swab-block and loop after the pressure is applied;

Figure 6 is a side view of a completed swab, the cap being in section; and

55 Figure 7 is an end view, from the left, of Figure 6.

In forming my new dauber I take a sheet A, of felt of suitable thickness, and grooved in both surfaces, by opposed grooves, a. The felt is preferably of soft and porous structure and may be a compound of felting and non-felting materials, as this is cheaper than a pure wool or hair felt and equally serviceable. The sheet after grooving is cut into strips along the ridges between the grooves, a, (see Figure 2) and the strips are then cut into suitable lengths to form swab blocks, B. A swab-block B is then surrounded by a wire loop, C, the bent end of which is inserted in a holder, D, and the free ends of the wire inserted in a chuck, E, which is then rotated, twisting the two wires together and drawing the parts of the loop between which is the swab-block as close together as desired, the effect of which is to force the bottoms of the grooves, a, toward each other and bring the sides, b, of the grooves toward each other, into opposed relationship to form a deep and narrow space in the body of the swab-block. The drawing of the surfaces, b, toward each other gives to the swab-block a substantially cylindrical shape (see Figure 3) which presents a smooth working surface of the greatest capacity, free from angles or projections.

In use the swab-block will absorb in its interstices the liquid to be applied. It will also hold in the space between the opposed surfaces, b, by capillarity, a quantity of liquid. The union of the swab-block B, and rod C is perfect and absolutely permanent. The compression of the swab-block by the twisting of the wire loop is very forceful and the resultant shaping of the swab block is favorable to the uses to which it is to be put, while the pressure applied is retained indefinitely by the friction of the twisted wire.

The method employed to attain these results is more economical than anything heretofore employed and the resulting dauber is more perfect for the uses to which it is designed to apply it.

In Figure 6, I show the completed article in its preferred form, the swab being associated, by means of the wire loop, C, with a cork F, through which the twisted ends of the wire loop are passed, and spread out along the outer end surface of the cork, as at C'. The cork is covered at its outer end by a

2
cap, G, the cork and cap being cemented together, so that the bent ends C' of the loop cannot move in any direction.

I claim:

5 The dauber or swab above described, consisting of a handle of twisted wire having an elongated loop at one end; a dauber-head, made up of two semi-cylindrical parts of soft

fabric, connected along the longitudinal center of their flat faces by a nexus of hard 10 fabric integral therewith, the nexus secured within the elongated loop.

Signed at Boston, Massachusetts, this twenty-sixth day of April, 1922.

CLEMENS A. HAASS.
